CONTROL FOR HEATING FURNACES

Filed July 2, 1923

2 Sheets-Sheet 2

Fig. 2.

UNITED STATES PATENT OFFICE.

ANDREW WOOD, OF CORNWALL ON THE HUDSON, NEW YORK.

CONTROL FOR HEATING FURNACES.

Application filed July 2, 1923. Serial No. 649,173.

To all whom it may concern:

Be it known that I, ANDREW WOOD, a subject of the King of Great Britain, residing at Cornwall on the Hudson, county of Orange, and State of New York, have invented certain new and useful Improvements in Controls for Heating Furnaces, of which the following is a specification.

My present invention relates to regulating means for furnaces used for heating buildings or houses.

The primary object of the invention is to provide a device whereby the damper of a heating furnace will be automatically opened and closed by the changes of atmospheric temperature acting on an electro-thermostat placed in any desired portion of the building.

Another object of the invention is to provide a device whereby the temperature may be maintained at a substantially uniform degree, thereby adding to the comfort of the occupants of the building and resulting in a great saving in the consumption of fuel which would ordinarily be required to bring the temperature to normal should the fire become low.

Another object of the invention is to provide a device which is simple in construction, requires a small amount of energy to operate, and one which may be easily attached to dampers in common use.

Other objects and advantages will be more clearly brought out in the following detailed description and accompanying drawings, wherein like reference characters designate corresponding parts throughout the several views, and wherein:

Figure 1 is a view partly in elevation and partly diagrammatic, showing the device as applied to a damper of a heating furnace.

Figure 2 is an enlarged elevation of the device shown attached to a damper of a heating furnace, a portion of the smoke pipe being shown in section.

Figure 3 is a vertical sectional view, taken on the line 3—3 of Figure 2, looking in the direction of the arrows and showing one face of a combined escapement and contact wheel forming a part of the invention.

Figure 4 is a vertical sectional view, taken on the line 4—4 of Figure 2, looking in the direction of the arrows and showing the opposite side of said wheel.

Figure 5 is a vertical sectional view, taken

on the line 5—5 of Figure 2, looking in the direction of the arrows and showing ratchet mechanism to permit of the raising of a weight.

Figure 6 is a diagrammatic view of the electric circuits of the device.

Referring to the drawings in detail, A designates generally a floor of a building; B, a heating furnace having the usual heating pipes C and smoke pipe D provided with a damper E; F my improved damper operating means comprising as escapement wheel G, electro-magnet H; armature I, weight operated drum J; J' a shaft for mounting said wheel and drum and a supporting bracket K therefor; L a circuit controlling means such as a thermostat and M a source of electrical energy, such as a storage battery or the like.

The heating furnace B may be of any preferred type, such as for hot air, hot water, or steam heat, the device being shown in the drawings as applied to a hot air furnace. The damper E of the smoke pipe D is of ordinary construction having a baffle plate 80 10 rotatable by a pin 11 which projects through the smoke pipe D and being provided at one end with a handle or the like 12.

The supporting bracket K may be secured 85 to a ceiling or a frame work of any kind which may be necessary in order to place the device in proper relation to the damper as by bolts 13. This bracket K in the example shown is provided with parallel depending 90 arms, 14, 15 and 16, and a depending arm 17 in a plane at a right angle to arms 14, 15, and 16. The arms 14 and 16 are provided with bearings 18 and 19 for receiving the shaft J' which is held against lateral movement by pins 20. The arm 17 forms a support for the electromagnet H which is preferably placed with the end of its cores in confronting relation to the periphery of the escapement wheel G for operating the armature I.

The shaft J' may extend for any desired distance out from the arm 16 and be forked at its outer end as at 21 for detachable connection with the handle 12 of the damper 105 E as by a screw or bolt 22.

The escapement wheel G which is rigidly mounted on the shaft J' between the arms 14 and 15 is preferably made of non-conductive material such as wood, hard rub- 110

ber, fibre or the like. Spaced at a right angle to each other and at the periphery of the escapement wheel G are four equidistantly spaced teeth 23 which are consecutively engaged by the armature I. Bridge pieces 24, 25, 26, and 27 are adapted to extend through the escapement wheel G and project a short distance out from each side thereof. The bridge pieces 24 and 25

10 are positioned diametrically opposite and relatively near the axis of said wheel and are in alignment with two of the teeth 23 while the bridge pieces 26 and 27 are positioned diametrically opposite and at a right 15 angle to and out of the path of travel of bridge pieces 24 and 25; said bridge pieces 26 and 27 being aligned with the other two teeth of said escapement wheel G.

The electromagnet H which may be of 20 any preferred type is held on the arm 17 by bolts or the like 28 and is adapted to draw the armature I out of engagement with the wheel G when a circuit is completed therethrough.

25 The armature I, having a hook 29 formed on its lower end for engaging the teeth 23 of the escapement wheel G may be pivoted as at 30 and be held in yieldable engagement with said wheel G by a spring 31.

30 The weight operated drum J is preferably mounted loosely on the shaft J' and carries a pawl 32 for engaging a ratchet wheel 33 which is secured against rotation on the shaft J'. This ratchet mechanism permits 35 of the raising of the weight 34, suspended by the rope or other flexible member 35; without rotating the shaft J'. One end of the rope 35 may be fastened to the supporting bracket K and the other secured to the 40 drum J. Handles 36 are provided on the drum in order to facilitate winding of the rope thereon.

The electrothermostat L may be of any 45 preferred type having the three contacts 37, 38 and 39 and having wires 40, 41 and 42 respectively leading therefrom.

Mounted on and insulated from the 50 depending arm 14 are two independent contact brushes 43 and 44 for engaging with one end of the bridge pieces 24, 25, 26, and 27. The brush 43 is placed in the path of one end of the bridge pieces 24 and 25 while the brush 44 is placed in the path of one end of the bridge pieces 26 and 27. It 55 can be clearly seen from Figure 3 of the drawings, that as the escapement wheel G is rotated, the brushes 43 and 44 will alternately engage their respective bridge pieces. The brush 43 is connected to the 60 contact 38 of the electrothermostat L by the wire 41, while the brush 44 is connected to the contact 39 of the electrothermostat L by the wire 42.

65 Mounted on and insulated from the depending arm 15 is a double brush 45 in the

path of the opposite ends of the bridge pieces 24, 25, 26 and 27 from that engaged by the brushes 43 and 44. The lips 46 and 47 of the brush 45 alternately engage the bridge pieces 24, 25, 26 and 27. The brush 45 is connected to one terminal of the electromagnet H by a wire 48.

One terminal of the battery M is connected to a terminal of the electromagnet H by a wire 49, while the other terminal of the battery M is connected to the contact 37 of the electrothermostat L by a wire 40.

The operation of the device is as follows: Assuming that the damper E is in a closed position as shown in Figure 2 of the drawings.

Due to the fall in temperature, the contact 37 engages contact 38 completing a circuit through wire 41, brush 43, bridge piece 25, brush 45, wire 48, electromagnet H, wire 49, battery M and through wire 40 back to contact 37. When the electromagnet H is energized, the armature I is drawn out of engagement with the tooth of the escapement wheel G, allowing the weight operated drum J through the pawl 32 and ratchet 90 wheel 33 to rotate the damper E through one quarter of a revolution. It can be clearly seen that when the escapement wheel G begins to rotate the circuit is broken by the bridge piece 25, moving out of contacting relation with the brushes 43 and 45, thereby allowing the spring 31 to draw the armature into operative engagement with the next tooth of the escapement wheel G for preventing more than a one-quarter revolution of the same. The bridge piece 27 has now moved into contacting relation with the brush 44 and lip 47 of the brush 45 in order that a circuit may be completed there-through when the temperature rises above 95 normal and results in engagement of the contacts 37 and 39. It will be noted that each time the electromagnet is energized, the result is a quarter turn of the damper.

100 When the weight approaches its downward limit, it may be again raised by manipulation of the drum. 110 Various changes may be made to the shape and size of the various elements shown and described, without departing from the spirit 115 or scope of the invention; but, I claim:

1. In combination with a damper for heating furnaces, a supporting bracket, a shaft mounted on the bracket adapted to be secured to said damper, an escapement wheel mounted rigidly on said shaft, co-acting conducting brushes positioned at opposite sides of said escapement wheel for making and breaking electrical circuits by movement of the escapement wheel, an armature engaging said escapement wheel, a thermostat, an electromagnet for drawing the armature out of engagement with said escapement wheel when a circuit is 120 125 130

completed through the coacting brushes by the thermostat, and means for imparting movement to said shaft.

2. In combination with a damper having a pivot pin provided with a handle, a supporting bracket, a shaft mounted on the bracket in axial alignment with said pivot pin and adapted to be secured to the handle of said damper, an escapement wheel mounted rigidly on said shaft, bridge pieces, carried by said escapement wheel located at different radii from the center thereof, co-acting conducting brushes in the paths of movement of said bridge pieces, an armature engaging said escapement wheel for normally holding it against rotation, a thermostat, an electromagnet for drawing the armature out of engagement with said escapement wheel when a circuit is completed through the co-acting brushes and bridge pieces by the thermostat, and means for imparting movement to said shaft.

3. In combination with a damper for heating furnaces, a supporting bracket, a shaft mounted on the bracket having a forked end for engagement with the damper, an escapement wheel of non-conductive material mounted rigidly on said shaft and provided at its periphery with four equidistantly spaced teeth, bridge pieces carried by said escapement wheel and projecting from each side thereof, coacting conducting brushes carried by but insulated from said supporting bracket, adapted to engage said bridge pieces on opposite sides of said escapement wheel, an armature normally held in engagement with one of said teeth of the escapement wheel for holding it against rotation, a thermostat, an electromagnet for drawing the armature out of engagement with said escapement wheel when a circuit is completed through the coacting brushes and bridge pieces by the thermostat, and means for imparting movement to said shaft.

4. In combination with a damper for heating furnaces, a supporting bracket, a shaft mounted on the bracket having a forked end for engagement with the damper, an escapement wheel of non-conductive material mounted rigidly on said shaft and provided at its periphery with four equidistantly spaced teeth, bridge pieces carried by said escapement wheel and projecting from each side thereof, adjacent bridge pieces being located at different radii from the center of said wheel, co-acting conducting brushes carried by but insulated from said supporting bracket, adapted to engage the opposite ends of the bridge pieces, an armature normally held in engagement with one of said teeth of the escapement wheel for holding it against rotation, a thermostat, an electromagnet for drawing the armature out of engagement

with said escapement wheel when a circuit is completed through the coacting brushes and bridge pieces by the thermostat, and means for imparting movement to said shaft.

5. In combination with a damper for heating furnaces, a supporting bracket, a shaft mounted on the bracket having a forked end for engagement with the damper, an escapement wheel of non-conductive material mounted rigidly on said shaft and provided at its periphery with four equidistantly spaced teeth, bridge pieces carried by said escapement wheel and projecting from each side thereof, independent contact brushes positioned at one side of said escapement wheel, adapted to alternately engage said bridge pieces, a double contact brush positioned at the other side of said escapement wheel, adapted to engage the opposite ends of the bridge pieces, an armature normally held in engagement with one of said teeth of the escapement wheel for holding it against rotation, a thermostat, an electromagnet for drawing the armature out of engagement with said escapement wheel when a circuit is completed through the coacting brushes and bridge pieces by the thermostat, and means for imparting movement to said shaft.

6. In combination with a damper of that character whereby upon a quarter turn the damper will be alternately opened and closed, a supporting bracket, a shaft mounted on the bracket having a forked end for engagement with the damper, an escapement wheel of non-conductive material mounted rigidly on said shaft and provided at its periphery with four equidistantly spaced teeth, bridge pieces carried by said escapement wheel and projecting from each side thereof, independent contact brushes positioned at one side of said escapement wheel, adapted to alternately engage said bridge pieces, a double contact brush positioned at the other side of said escapement wheel adapted to engage the opposite ends of the bridge pieces, an armature normally held in engagement with one of said teeth of the escapement wheel for holding it against rotation, a thermostat, an electromagnet for drawing the armature out of engagement with said escapement wheel when a circuit is completed through the coacting brushes and bridge pieces by the thermostat, and means mounted upon the shaft for revolving the shaft through one-quarter of a revolution when the armature is drawn out of engagement with the escapement wheel.

7. The combination with a rotatable element, a thermostat, a shaft secured to said rotatable element, a circuit reversing means comprising a wheel of non-conductive material rigidly mounted upon said shaft, diametrically aligned bridge pieces carried by said wheel at a point relatively near the

axis thereof and projecting from each side of the wheel, diametrically aligned bridge pieces carried by said wheel at a point relatively near the periphery thereof and projecting from each side of the wheel, said second mentioned bridge pieces lying out of diametric alignment with said first mentioned bridge pieces, a contact brush positioned at one side of said wheel provided 10 with lips lying in the path of said bridge pieces, adapted to alternately engage said

bridge pieces and independent contact brushes positioned at the other side of said wheel, in the path of said bridge pieces, adapted to alternately engage the opposite 15 ends of the bridge pieces for sending an electrical current first through one circuit and then through another; an electromagnet associated with said wheel and means for imparting movement to said wheel when 20 released by said magnet.

ANDREW WOOD.
